UNITED STATES PATENT OFFICE.

CHRIS SPASOFF, OF BERKELEY, CALIFORNIA.

BURNISHING-WHEEL COVER.

1,382,254.

Specification of Letters Patent. Patented June 21, 1921.

Application filed October 9, 1920. Serial No. 415,880.

To all whom it may concern:

Be it known that I, CHRIS SPASOFF, a citizen of the United States, residing at Berkeley, in the county of Alameda and State of California, have invented new and useful Improvements in Burnishing-Wheel Covers, of which the following is a specification.

This invention relates to burnishing or buffing wheels, such as are used in the finishing of shoes, and consists in an improved construction of removable cover for such wheels whereby considerable economy and efficiency are required over the common practice.

15 Heretofore, where burnishing wheels have been provided with removable covers, the latter have either been made entirely of fabric, such as canvas, or of leather; in the former case, their durability was slight and, in the 20 latter case, their efficiency was slight, owing to the difficulty of attaching the cover smoothly to the wheel and to the lack of porosity of the leather buffing surface.

I have demonstrated in practice that a 25 cover, constructed in accordance with my present invention, partly of leather or other relatively heavy, pliable burnishing material and partly of canvas, or other textile material, and so as to be applied in the manner hereinafter described, overcomes the disadvantages heretofore found in the practical use of such removable covers and results in very considerable economies.

The invention is illustrated in the accompanying drawing, in which,

35 Figure 1 is a side elevation of a wheel, equipped with my improved cover and partly broken away. Fig. 2 is a perspective view with the cover partly applied. Fig. 3 40 is a detail cross-section of one edge of the cover, and Fig. 4 is a detail cross-section through the overlapping end edges of the cover. In these views, 1 represents the hub of the wheel, mounted on the shaft 2, and 3 45 the usual periphery of felt or rubber, firmly secured on the hub. 4 represents one of the nuts or clamping plates, threaded on the shaft and securing the wheel thereon. These parts are of the usual construction.

50 My improved removable cover is composed of a strip 5 of soft porous leather, preferably what is known as "Korrey-Krome" leather. It may be provided with a plurality of small perforations 6, to constitute wax-retaining pores, as shown in Fig. 2. The strip 5 is of a length to fit

around the periphery of the wheel, the leather at the ends being skived or slightly thinned, as indicated at 7, to provide for an overlap without any bunching. The longitudinal edges 8 are also slightly thinned and to them are stitched at 9 the folded edges 10 of strips of doubled canvas 11, or the like. The leather strip is of greater width than the periphery of the wheel, the thinned edges being intended to be bent over the sides of the wheel, so that the canvas strips will not come in contact with the work being burnished.

Through the doubled canvas strips is 70 passed a cord or draw string 12, the central portion of which forms a loop 13, extending from end of the cover and sewed to the adjacent ends of the canvas strips at 14. The ends of the cord pass freely through said 75 strips and extend beyond the ends thereof, as shown at 15, 15.

To apply the cover to a wheel, the loop 13 is engaged across the periphery and the cover is then wrapped around the wheel, which has 80 the effect of winding the side portions of the loop around the shaft on each side of the wheel, as shown at 16, 16, causing the cover to be drawn tightly over the periphery. The free ends 15, 15 of the cord are then drawn 85 up tight, causing the canvas strips to be gathered or plaited against the sides of the wheel, as shown, and then the nuts or clamping plates are tightened up to hold said strips in that condition. In this way the thinned 90 edges of the leather strip are pulled down snugly over the side faces of the wheel and the body of said strip is applied smoothly and firmly to the periphery.

Having thus described my invention, what 95 I claim is:

1. A burnishing wheel cover, composed of a central strip of soft leather, and strips of textile material secured to the same along its longitudinal edges, and means secured 100 to said textile strips to bind the cover on the wheel.

2. A burnishing wheel cover, composed of a strip of soft and porous leather, thinned at its edges so as to be flexible, and lateral 105 strips of canvas or the like, secured to the longitudinal edges of said leather strip, and provided with means to gather their edges to cause the leather strip to tightly hug the wheel.

3. A burnishing wheel cover, composed of a strip of perforated leather, and strips of

textile material secured to the longitudinal edges thereof, the latter adapted to be turned down over the sides of the wheel and secured in attaching position.

- 5 4. A burnishing wheel cover, consisting of a strip of perforated leather, thinned at its ends and edges, a strip of doubled canvas sewed to each edge of said leather strip, a loop of cord secured to one end of each 10 canvas strip, and a draw cord in each canvas strip and secured thereto at the same ends as said loop.
5. A burnishing wheel cover consisting of

a band of heavy pliable material of slightly greater width than the face of the wheel, a 15 strip of thin flexible material secured to each longitudinal edge of said band, and a gathering cord in the free edge of each of said strips.

In testimony whereof I have hereunto set 20 my hand.

CHRIS SPASOFF.
